INDIVIDUAL WASH FOUNTAIN

Filed Nov. 25, 1927

UNITED STATES PATENT OFFICE

LOUIS SCHLESINGER AND HERMAN E. HEINE, OF MILWAUKEE, WISCONSIN, AS
SIGNORS TO BRADLEY WASHFOUNTAIN COMPANY, OF MILWAUKEE, WISCONSIN,
A CORPORATION OF WISCONSIN

INDIVIDUAL WASH FOUNTAIN

Application filed November 25, 1927. Serial No. 235,592.

This invention relates to improvements in individual washfountains, and more particularly to the sanitary type in which flowing water is used for washing.

It is one of the objects of the present invention to provide an individual washfountain having an adjustable discharge valve to discharge water through a spray head in a thin, semi-circular or crescent shaped sheet of water, and so arranged as to strike the washfountain bowl beyond and practically surrounding the bowl drain opening, whereby the bowl is continuously flushed while the water is being discharged, of all used water, dirt, soapsuds, etc.

A further object of the invention is to provide an individual washfountain in which the spray head therefor is arranged to discharge into the washfountain bowl a thin, crescent shaped sheet of water, said spray head being positioned a sufficient distance above the bowl to permit ablution in the sheet of water therebetween.

A further object of the invention is to provide an individual washfountain supported upon a standard and which may also be conveniently connected to the side wall of a room in a very simple manner.

A further object of the invention is to provide an individual washfountain in which water is supplied thereto for washing purposes by a combination spray head and valve, the latter having a single positive shut off valve controlling the flow of water from both hot and cold water inlets and permitting the mixing of water to be discharged to any desired temperature and in any desired quantity, and further permitting the independent regulation of the volume of flow without affecting the temperature, or permitting changes in temperature without affecting the volume of flow.

A further object of the invention is to provide an individual washfountain which is of very simple construction, is strong and durable, and is well adapted for the purposes described.

With the above and other objects in view the invention consists of the improved individual washfountain, and its parts and com-

bination, as set forth in the claim, and all equivalents thereof.

In the accompanying drawing in which the same reference characters indicate the same parts in all of the views:

Fig. 1 is a vertical sectional view of the improved individual washfountain, part being broken away;

Fig. 2 is an enlarged detail sectional view thereof taken on line 2-2 of Fig. 1;

Fig. 3 is a detail cross sectional view taken on line 3-3 of Fig. 2; and

Fig. 4 is a detail sectional view taken on line 4-4 of Fig. 1 and on a larger scale.

Referring to the drawing it will appear that the numeral 8 indicates the basin or bowl of the improved lavatory, 9 the tubular standard or support therefor, and the fountain or spray head which supplies the water for washing is indicated generally by the numeral 10. The lavatory may be constructed of any suitable material desired, and the top is preferably of circular form in plan view, while the basin or bowl portion is of less width at its rear to form a flange or apron 11, which permits attachment to a side wall, if desired. The bowl or basin 8 is formed in its lower portion with a central strainer and outlet opening 12 connected to a trapped discharge pipe 13 which extends rearwardly into a side wall and to a point of discharge.

Extended vertically through the apron portion 11 is an elongated tubular member 14 having a flanged upper end 14' against which a collar 15 rests to support the upper portion of said member above the bowl, a clamping nut 16 being threaded onto an intermediate portion of the tubular member 14 below said apron portion 11.

A coupling member 17 surrounds the lower end portion of the member 14 and nipples 18 and 19 enter opposite sides of said coupling member and register with reduced openings 20 and 21 therein. Said nipples connect with elbows 22 and 23 from which extend, respectively, hot and cold water supply pipes 24 and 25 which lead to sources of supply and are each provided with a valve 26.

Secured to the upper end portion of the tubular intermediate member 14 above the

bowl 8 is a hollow bell-shaped spray head 27. The interior of the same is divided by a horizontal partition 28. There is also, in the lower portion of the spray head, and connected with the horizontal partition, a diametrically extending, centrally enlarged, vertical partition 29, defining a discharge chamber 30 and an inlet chamber 31. The lower portion of the outer wall of the head adjacent the discharge chamber is provided with a semi-annular spray vent 32 formed of one or more elongated slots. Water is adapted to be discharged through said spray vent for washing purposes in a crescent shaped sheet, as indicated at 33, and the wall adjacent said vent must be of a substantial thickness as the frictional engagement between the flowing water and the vent surfaces is one of the agencies responsible for the formation of the peculiar thin sheet of water discharged and prevents ruptures or breaks in the discharged sheet.

As shown, the spray head is formed of separable upper and lower sections, and extended through the top of the upper section is a bushing 34 which is threaded at its lower end portion into a second bushing 35 which, in turn, is threaded into the partition 28. It should be observed that the centrally enlarged portion of the vertical partition 29 is formed with a bore 36, a portion of which is threaded and communicating with the tubular member 14, and extended through the bushings 34 and 35, the bore 36 and in threaded engagement with the latter, and into the member 14, is an elongated valve rod 37. As shown in Fig. 2, the lower portion of the bore 36 is enlarged to provide clearance between it and the valve rod, and said bore communicates, by means of ports 38, with the inlet chamber 31. A rib 39 is formed around the lower portion of the bore 36 to provide a valve seat. Adapted to operate against said valve seat to control admission to said bore is a valve 40 mounted fast on an intermediate portion of said valve rod. For the purpose of turning the valve rod to vary the disposition of said valve with respect to its seat, the exterior projecting portion of the valve rod carries an operating handle 41.

When the valve rod is turned to seat the valve 40 the lower end portion of said rod is slightly above and spaced from the lower closed end portion of the tubular member 14. A cup shaped mixing valve 42 is revolvably mounted against the inner wall of the lower portion of said member 14 and is carried by said rod 37. The adjacent portion of the member 14 is provided with a pair of opposed ports 43 and 44 registering with the reduced openings 20 and 21 and the mixing valve is formed with a pair of elongated, adjacent ports 45 and 46 adapted to be brought into registration with one or both of said ports 65 43 and 44.

Extended through a side wall of the spray head 27, immediately below the horizontal partition 28, is a threaded bushing 47, into which is threaded a stem 48 carrying a knob or hand wheel 49 at its outer end portion. The bore 36 in the partition 29, immediately above the threaded portion, is enlarged, as in Fig. 2, and communicates with a transverse port 50 in said partition 29, affording communication between the spray head inlet chamber 31 and the outlet chamber 30.

The inner end portion of the bushing 47 terminates adjacent an end of the port 50, and an inward or outward movement of the stem 48 varies the relative restriction to the end of the port 50 to increase or decrease the flow of liquid from said port into the chamber 30.

The operation of the device is as follows: By turning the handle 41, the valve rod 37 is turned to disengage the valve 40 from its seat. At the same time, the mixing valve 42 is turned therewith to allow either or both of the ports 45 and 46 to register with one or both of the ports 43 and 44, as desired whereby water is admitted into the mixing valve from either the hot or cold water pipes, or both. Thus the exact temperature of water desired may be obtained. Water entering the mixing valve flows upwardly through the tubular member 14 and past the opened valve 40, through the ports 38 and into the spray head chamber 31. As previously described, the stem 48 can at any time be turned to regulate the amount of water flowing into the spray head outlet chamber from whence it is discharged through the spray vent for washing purposes in a thin semi-annular, or crescent shaped sheet. This discharged sheet of water strikes the bowl in a curved line well removed from the drain opening and thereby serves to continuously and efficiently flush the bowl.

It is, therefore, obvious that the improved individual washfountain is constructed to permit the discharge of tempered water in any desired quantity. The water may be tempered independently of the volume control and the volume may be varied without affecting the temperature of the water resulting from an adjustment of the mixing valve. The device includes only one positive shut off valve controlling the flow from both hot and cold water pipes and the same operates with the mixing valve. The water is discharged from the spray head in a novel manner in the form of a thin crescent shaped sheet for ablutions, and said sheet continuously flushes the bowl.

What is claimed as the invention is:

A spraying device, comprising a tube, hot and cold water supply pipes connected therewith, a mixing valve within said tube, a single shut-off valve within the tube inwardly of the mixing valve, a common means extending exteriorly of said tube for jointly operat-

ing said mixing valve and said shut-off valve, and a spray head connected to the upper end portion of the tube and provided with an exteriorly extending volume regulatory valve, said spray head having a semi-annular discharge vent.

In testimony whereof, we affix our signatures.

LOUIS SCHLESINGER.
